UNITED STATES PATENT OFFICE.

SIDNEY S. SMITH, OF SENECA FALLS, NEW YORK, ASSIGNOR TO THE GOULDS MANUFACTURING COMPANY, OF SENECA FALLS, NEW YORK, A CORPORATION OF NEW YORK.

DESIGN FOR A POWER-PUMP OR SIMILAR ARTICLE.

41,271.

Specification for Design.

Patented Mar. 28, 1911.

Application filed May 12, 1910. Serial No. 561,018. Term of patent 14 years.

To all whom it may concern:

Be it known that I, SIDNEY S. SMITH, a citizen of the United States, residing at Seneca Falls, in the county of Seneca and State of New York, have invented a new, original, and ornamental Design for a Power-Pump or Similar Article, of which the following is a specification, reference being had to the accompanying drawings, forming a part thereof.

The drawings which exemplify my new

design of power pump or similar article show by Figures 1 and 2, respectively, a right and a left side elevation thereof.

I claim:

The ornamental design for a power pump or similar article as shown.

SIDNEY S. SMITH.

Witnesses:

N. G. GOULD,
H. S. FREDENBURGH.

Copies of this design may be obtained for five cents each, by addressing the "Commissioner of Patents, Washington, D. C."
